BY *John A. Diederich,* ATTORNEY.

UNITED STATES PATENT OFFICE.

CHRISTIAN H. GOEBEL, OF PHILADELPHIA, PENNSYLVANIA.

BEDSTEAD-FASTENING.

SPECIFICATION forming part of Letters Patent No. 270,051, dated January 2, 1883.

Application filed June 27, 1882. (No model.)

To all whom it may concern:

Be it known that I, CHRISTIAN H. GOEBEL, a citizen of the United States, residing in the city and county of Philadelphia, State of Pennsylvania, have invented a new and useful Improvement in Bedstead-Fastenings, which improvement is fully set forth in the following specification and accompanying drawings, in which—

10 Figure 1 is a side elevation of the bedstead-fastening embodying my invention. Fig. 2 is a horizontal section in line *xx*, Fig. 1. Fig. 3 is a vertical section in line *yy*, Fig. 1, the post being partly broken away.

15 Similar letters of reference indicate corresponding parts in the several figures.

My invention consists of a bedstead-fastening which is simple, inexpensive, strong, and durable, the parts thereof being on the 20 outside of the wood-work, thus avoiding open places, and consequently preventing the lodgment of vermin.

It also consists of the peculiar construction of the plates which are connected with the 25 head and foot posts, whereby they are prevented from being withdrawn from position, as hereinafter described and claimed.

Referring to the drawings, A represents one of the posts of a bedstead, and B one of 30 the side rails thereof.

C D represent two metallic plates, and E represents a metallic key or wedge, forming together the fastening for the post and rail. The plate C is secured to the rail B, or may 35 be secured to the post A, and has on its outer face, at top and bottom, at the end adjacent to the post, two vertical lips, F, whose inner faces are dovetailed or otherwise grooved. The portion of the plate C between the lips F 40 is cut away or grooved, and into the space *a* thus formed projects the plate D, which is fastened to the post A, or may be secured to the rail B, and the end of the plate in said space having a vertical lip, G, the inner face 45 of which is dovetailed or otherwise grooved, it now being noticed that the groove of the lip G faces the grooves of the lips F, and the lip G is sufficiently separated from the lips F to receive between them the key E, 50 which is of wedging form and has dovetailed sides.

It will be seen that when the plates C D are in position, and the key E is inserted between the lips F G and driven downwardly, 55 the key, owing to its wedging shape, forces

the lips from each other, and consequently draws the post and rail firmly against each other, the dovetailed or grooved nature of the lips and key preventing disengagement of the parts and producing a reliable fastening. 60

It will be seen that the plates and key may be made strong and durable, and all parts are simple and inexpensive. Furthermore, both plates and key are on the outside of the 65 post and rail, and there are no openings in which vermin may enter and lodge.

For the purpose of securing the plate D to the post, said plate has at the side opposite to its lip a flange, D'. An opening is made 70 in the post sufficiently large to pass the lip or the flange through it, said flange then being located on the back of the post against the solid part thereof and overhangs the edge of the opening, the remainder of the opening not 75 occupied by the shank of the plate being filled by a piece, H, preferably of wood, said piece thus preventing lateral displacement or shifting of the plate D in the post and consequent withdrawal of said plate from the post. The 80 flange D' is serrated or corrugated, so as to interlock with the wood of the post, thus providing additional security for the connection of the plate with the post, and preventing it from turning in the opening occupied by its 85 shank.

Having thus described my invention, what I claim as new, and desire to secure by Letters Patent, is—

1. The bedstead-fastening consisting of two 90 plates with grooved lips and a wedging-key, substantially as described, one plate projecting into the space of the other, thus placing the respective lips on opposite sides and receiving between them the key, which, being 95 tightened against the lips, serves to draw the post and rail toward each other, in the manner stated.

2. The post formed with an opening and having a filling-piece, in combination with the 100 connected plate formed with a flange, substantially as and for the purpose set forth.

3. The fastening-plate having a flange formed with serrations, substantially as and for the purpose set forth.

CHRISTIAN H. GOEBEL.
